Patented Aug. 27, 1918.

UNITED STATES PATENT OFFICE.

JOHN MCKENNEY, OF ANACONDA, MONTANA.

CARBURETOR.

1,276,587.

Specification of Letters Patent Patented Aug. 27, 1918.

Application filed September 18, 1916. Serial No. 60,886.

To all whom it may concern:

Be it known that I, JOHN MCKENNEY, a citizen of the United States, residing at Anaconda, in the county of Deerlodge and State of Montana, have invented a new and useful Carburetor, of which the following is a specification.

This invention has reference to means for producing gas by enriching air with a volatile hydrocarbon, and its object is to provide such a means furnishing different qualities of carbureted air at small cost and by which carbureted air suitable for various purposes is readily manufactured by a simple manipulation of a controlling valve.

In accordance with the present invention air is directed through a series of tanks containing volatile liquid, such, for instance, as gasoline with the gasoline automatically renewed and the air which is supplied under pressure is controllable to be directed at will through the enriching tanks or into a collecting tank in which the enriched air accumulates.

By means of a suitable readily controllable valve interposed in an air pipe leading from an air compressing pump the air is directed through all the gasoline tanks and finally into a receiver in a highly enriched state, or is directed into the receiver without passing through the gasoline tanks, or the air is caused to divide, part of it passing through the gasoline tanks and part of it directly into the receiver. At no time, however, is the air entirely cut off by the valve from the receiver. Because of this it is possible to produce full enriched air which may serve for illuminating purposes, or a product considerably diluted with air and which therefore provides a highly explosive mixture suitable for gas engines. Carbureted air weak in hydrocarbons to an extent making it highly explosive is also useful for producing great heat especially if used in conjunction with acetylene gas, so that it may be used for smelting or for any other purpose where great heat is desired.

The apparatus is provided with a telltale flame enabling the operator to readily control the production of the carbureted air in accordance with the use intended.

The invention will be best understood from a consideration of the following detailed description, taken in connection with the accompanying drawings forming part of this specification, with the further under-

standing that while the drawings show a practical form of the invention, the latter is not confined to any strict conformity with the showing of the drawings, but may be changed and modified so long as such changes and modifications come within the scope of the appended claim.

In the drawings—

The figure is a more or less diagrammatic view with parts in section of an apparatus embodying the present invention.

Referring to the drawings, there is shown a number of tanks 1, 2, 3, 4, although it will be understood that the number of tanks employed is not necessarily limited to the number illustrated, since either less or more than four may be employed under certain circumstances. The tanks are closed tanks and each near the bottom, the tanks being upright, is provided with a diametric screen diaphragm 5. The mesh of the screen is made fine enough to avoid the passage of particles which might impede burners or other means of utilizing the gas produced. At the bottom each tank is entered by a nipple 6 and the nipples are all connected together by a common pipe 7, so that at the bottoms the tanks are all in communication. The tank 1 at the top is connected by a pipe 8 to the top of tank 2, the pipe 8 having a continuation 9 extending to near the bottom of the tank 2 and below the diaphragm 5 thereto. The tank 2 is similarly connected by a pipe 10 to the tank 3 and the pipe 10 has a continuation 11 opening within the tank 3 near the bottom thereof also at a point below the diaphragm 5 of tank 3. Likewise the tank 3 is connected by a pipe 12 to the tank 4, and the pipe 12 has a continuation 13 opening into the tank 4 below the diaphragm 5 thereof. The pipes 10 and 12, like the pipe 8, lead from the top of one tank and open near the bottom of the next tank in order.

Loading from the top of tank 4 is another pipe 14 carrying a gas jet 15 provided with a controlling valve 16. The pipe 14 leads into a gas-receiving tank 17 provided with a blow-off valve 18 and from the tank 17 there leads another pipe 19 to any desired point of utilization of the enriched air.

There is also provided an air pump 20 more or less diagrammatically indicated in the drawings, since any type of air pump capable of supplying air under pressure may be used. Where the system of the present in-

vention is installed upon a farm or in other similar localities, a windmill may supply the power for driving the pump 20. In other locations water pressure may be employed 5 for a like purpose, and under still other circumstances, and especially where the gaseous product is employed for driving a gas engine, power from the engine may be utilized to drive the pump 20. The air delivered 10 from the pump 20 is directed through a pipe 21 to a valve casing 22 provided with adjacent ports 23, 24, respectively. These ports are under the control of a valve 25 which may be moved by a rack 15 26 and pinion 27, the latter being actuated by a crank 28. The ports 23 and 24 are so related to the valve 25 that either port may be entirely open with the other closed, or both ports may be opened to like extents or either 20 port to a greater extent than the other port at the same time. Leading from the port 23 is a pipe 29 including a check valve 30 closing toward the valve casing 22. The pipe 29 discharges into the bottom of the tank 1. 25 Leading from the port 24 is another pipe 31 extending to and discharging into the tank 17.

All the tanks 1 to 4 contain a quantity of 30 liquid 32, which liquid may consist of gasoline or other suitable volatile material, of which gasoline may be taken as an example.

There is also provided a tank 33 designed 35 to contain a supply of gasoline, and hence may be termed a gasoline storage tank. The tank 33 discharges through a pipe 34 into another tank 35 and the pipe 34 contains a valve 36 which may be an ordinary globe valve or any other suitable type of valve. The tank 35 has a gage glass 37 and 40 a filling opening 38 normally closed by a cap or plug 39. The top of the tank 35 is connected to the top of the tank 1 by a pipe 40 containing a valve 41. The tank 35 is conveniently supported on a bracket 42 45 which may be carried by the tank 1 and leading from the tank 35 at a low point thereof is a pipe 43 containing a valve 44 and opening into the tank 1 where it terminates in a float valve 45 controlled by a 50 float 46 in the usual manner. The tank 33 is provided with a gage glass 47 and leading into the bottom of the tank is a pipe 48 provided with a valve 49. Where water under pressure is convenient the pipe 48 is 55 connected to a source of water supply.

Assuming the valve 49 to be closed and the various tanks to be empty, gasoline is poured through the filling opening 38 into the tank 35 and the valves 41 and 44 being 60 open the gasoline finds its way into the tanks 1, 2, 3 and 4 until its flow thereinto is stopped by the rising level of the gasoline engaging the ball 46 and closing the valve 45. Now if the valve 36 has been opened, 65 gasoline will flow into the tank 33 until the

latter is full, or the valve 36 may be opened after the other tanks are full.

Now, with the valve 41 closed the valve 49 is opened, and water under pressure tends to enter the tank 33, which, however, it cannot do so long as the valve 45 is closed. When the level of gasoline in the tanks 1, 2, 3 and 4 lowers, this level being the same for all the tanks, the valve 45 is opened and the water pressure exerted through the pipe 75 48 tends to cause a flow of the gasoline from the tank 33 into the tank 35 and from the latter into the tank to be distributed by the pipe 7 and nipples 6 into the various tanks 1, 2, 3 and 4 always to the same 80 level. The gage glass 47 readily shows increasing amount of water in the tank 33 and diminishing amount of gasoline until it becomes necessary to replenish the gasoline supply in the tank 33, which is easily accomplished by draining the tank 33 of the water in any suitable manner, after which the supply of gasoline may be replenished through the filling opening 38 in the manner already described. 85

Considering the tanks 1, 2, 3 and 4, as properly supplied with gasoline, and if it be assumed that the pump 20 is in operation with the valve 25 so positioned as to open the port 23 and close the port 24, air is 90 pumped into the bottom of the tank 1 and bubbles up through the gasoline therein becoming enriched to an appropriate extent. The enriched air flows from tank 1 to tank 2 and then bubbles up through the gasoline 95 therein to become further enriched and so on until reaching the pipe 14, it being assumed that there is either increasing pressure being established within the tank 17 or the air 100 therein is allowed to escape through the valve 18 then open for the purpose or through the pipe 19. As soon as a flame can be obtained at the burner 15 the operator knows that enriched air is passing to the tank 17 and the richness of this air is 105 demonstrated by the character of the flame. Usually this flame will burn brightly, thus indicating highly enriched air suitable for illuminating or cooking purposes. If such air be stored in the tank 17 it may be employed at any time for such purpose as desired, and if the tank 17 be made sufficiently large it will contain an ample supply of enriched air for use when the pump 20 is not 110 in operation. Suppose, however, that it is 115 desired to employ carbureted air of a different character, say, one of an explosive nature suitable for an explosion engine. In such case the valve 25 is moved to a position either to wholly close the port 23 and wholly 120 open the port 24, or provide some proportional opening of both. Under these circumstances if the port 23 be wholly closed ordinary air without any enriching flows into the tank 17, there mixing with the rich air 125

already assumed to be within the tank 17 under pressure, and the rich air is correspondingly diluted, but made highly explosive, so as to be particularly adapted for explosion engines, or for those conditions where great heat is demanded, such as smelting and the like, or for cutting and welding operations as performed by the blow pipe.

The diaphragms 5 are particularly useful 10 in breaking up the bubbles of air escaping from the air inlet pipes to the various tanks, whereby the enriching of the air is correspondingly facilitated.

By the constant level arrangement for all 15 the tanks a uniformity of enriching is insured.

The enriched air is cheaply produced and is readily provided in various useful conditions. When the apparatus is arranged to 20 operate an explosion engine, it is unnecessary to crank the engine, since the product is supplied to the engine under pressure and is already an explosive mixture, wherefore ignition alone is all that is needed to start the 25 engine.

In country places where wind power must usually be depended upon for providing the needed pressures the gas-receiving tank 17 may be charged when wind is available and 30 this charge may be used during times of calm.

A test flame burning at the burner 15 may be employed to apprise the operator of the condition of the enriched air being delivered 35 to the receiving tank 17.

The tank 35 serves as an auxiliary supply tank, since with the valves 41 and 44 open and the valve 36 closed the gasolene from the tank 35 will flow as permitted by the 40 valve 45 until the gage glass 37 shows that

the supply is getting low, whereupon the tank 35 is replenished by opening the valves 36 and 49 and after the tank 35 is again filled the valves 36 and 49 may be closed, or the valve 36 alone if closed will hold back gas- 45 olene from the main supply tank 33.

What is claimed is:—

A carbureter comprising a plurality of containers for volatile hydrocarbon liquid all connected together in multiple at a low 50 point, pipes connecting each container at a high point to a low point of the next container in order, means for maintaining a predetermined level of liquid in all the containers through the multiple connections at 55 low points of the containers, a storage tank for carbureted air, a connection between the last container in order and the storage tank, an air pump, a valve connected to the discharge side of the air pump, a pipe leading 60 from the valve to the first container in order at a low point thereof and provided with a check valve opening toward the container, and another pipe leading from the valve to the storage tank, said valve having a range 65 of movement to connect it to either pipe alone or to both pipes simultaneously at will, whereby air may be progressively enriched by being successively passed through a plurality of like quantities of hydrocarbon 70 liquid, or the enriched air may be diluted with other air, or both operations may be performed at the same time.

In testimony, that I claim the foregoing as my own, I have hereto affixed my signature in the presence of two witnesses.

JOHN MCKENNEY.
